UNITED STATES PATENT OFFICE

90,769

DESIGN FOR AN EDUCATIONAL APPLIANCE

Abraham L. Kamen, Brooklyn, N. Y.

Application July 24, 1933. Serial No. 48,804

Term of patent 7 years

To all whom it may concern:

Be it known that I, ABRAHAM L. KAMEN, a citizen of the United States, residing at Brooklyn, in the county of Kings and State of New York, have invented a new, original, and ornamental Design for an Educational Appliance, of which the following is a specification, reference being had to the accompanying drawing, forming part thereof, in which:

Fig. 1 is a perspective of the educational appliance comprising a foldable blackboard and

crayon set attached thereto, the blackboard being folded; and

Fig. 2 is a perspective of the appliance, the blackboard being partly unfolded and the cover of the crayon set removed but in proximity thereto.

I claim:—

The ornamental design for an educational appliance as shown and described.

ABRAHAM L. KAMEN.
